UNITED STATES PATENT OFFICE.

WILLIAM J. GOURIE, OF PHILADELPHIA, PENNSYLVANIA.

KNITTING DEVICE.

Application filed September 15, 1926. Serial No. 135,535.

My invention relates to knitting devices and more particularly to hand knitting devices adapted to knit fabrics in strands.

Knitting fabrics in strands by means of pegs driven in the end of a spool-shaped structure is well known but has the disadvantage that any one device will produce but one size and shape of strand. Further the flange on the upper side of the device, in which the pegs are placed, interferes with the ready manipulation of the strand of yarn.

One of the objects of my invention is to produce a device on which strands of various sizes may be knitted and which has no parts tending to interfere with the easy operation of the device.

Another object of my invention is to produce a device whereby loosely knitted or tightly knitted strands may be produced at the will of the operator.

A further object of my invention is to produce a device on which different kinds and various sizes of material may be knitted.

These objects and other advantageous ends which will be described hereinafter, I attain in the following manner, reference being had to the accompanying drawing in which

Figure 1 shows a preferred embodiment of my invention,

Figure 2 illustrates the first step of a knitting operation,

Figure 3 the second step,

Figure 4 the third step, and

Figure 5 shows a partially knitted strand of fabric.

Referring now more particularly to Figure 1, the preferred form of my invention consists of a single piece of wire bent near its center, as indicated at 6, into V-shape with the central portion of each leg of the V bent into a loop or ring 7 and with the outer end 8 extending at right angles to but outside of the body portion 9 of the V.

Referring now to Figures 2, 3, 4 and 5; a strand of yarn 10 is first looped around the ends 8 in the shape of a figure 8 and then carried across the parallel faces of the ends above the body portion, as shown in Figure 2. One of the loops of the figure 8 is slipped up over the end of the part 8 and then pulled downward until it rests on the adjacent strand, as shown at 11 in Figure 3.

The yarn 10 is then given one-half turn around both parts 8 and the opposite loop

of the figure 8 is slipped over the end of the part 8 and then pulled downward against the adjacent strand, as shown at 12 in Figure 4. The process is thus continued by alternately slipping the lower strand of yarn over the end of the part 8 so that the loop thus formed rests on top of the strand 10 and giving the strand 10 a half turn about the parts 8 of the device. The knitted portion will depend between the rings 7 as shown by the knitted strand 13 in Figure 5.

By spreading the ends 8 farther apart, strands of greater cross-sectional area but loosely knitted may be produced and, by bringing the ends 8 closer together, more tightly knitted strands of lesser cross-sectional area will be produced. Where larger knitted strands are desired, heavier material or a plurality of yarns may be used. The device is also adapted for knitting strips, braids, carpet-rags, etc., into strands. The strands thus knitted may be disposed side by side in any preferred form and the adjacent strands stitched together to form table mats, floor rugs, etc. The device is better adapted to the amusement of children than any of the older types of devices of this kind.

While a device of any particular size will produce a wide range of sizes of knitted strands, the device may be made in various sizes.

While I have described my invention as taking a particular form, it will be understood that various changes may be made therein without departing from the spirit of the invention, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A hand knitting device having an open V-shaped body portion, loops formed below and integral with the body portion, and yarn engaging pins extending upwardly from and integral with the said loops.

2. A hand knitting device formed from wire and having a V-shaped body portion, loops formed in each leg of the V, and the ends of the wire extending from the loops at right angles to the body portion and adapted to be bent inwardly and outwardly for producing smaller or larger strands.

3. A hand knitting device having an open

V-shaped body portion, each end of the V-shaped portion having an extension adapted to engage the material to be knitted and projecting at right angles to the plane of the V-shaped portion.

4. A hand knitting device having a body portion and extending yarn engaging pins

in a plane at an angle to that of the body portion, said pins being adapted to be adjustably positioned to vary the space therebetween.

In testimony whereof I have signed my name to this specification.

WILLIAM J. GOURIE.
